UNITED STATES PATENT OFFICE.

JAMES McKECHNIE, OF BARROW-IN-FURNESS, ENGLAND, ASSIGNOR TO VICKERS LIMITED, OF WESTMINSTER, ENGLAND.

TWO-STROKE INTERNAL-COMBUSTION ENGINE.

1,318,781.

Specification of Letters Patent. Patented Oct. 14, 1919.

Application filed May 1, 1918. Serial No. 231,843.

To all whom it may concern:

Be it known that I, JAMES McKECHNIE, a subject of the King of Great Britain, residing at Naval Construction Works, Barrow-in-Furness, in the county of Lancaster, England, have invented certain new and useful Improvements in or Relating to Two-Stroke Internal-Combustion Engines, of which the following is a specification.

10 This invention relates to two-stroke internal combustion engines, and has for its chief object to reduce the loss of scavenging air and thus to increase the efficiency of the engine. In engines of this kind, whether of 15 the single or opposed piston type, in which the exhaust escapes through ports covered and uncovered by the piston, a considerable loss of scavenging air takes place through the open ports and the amount of air left in 20 the cylinder for compression is measured from the cut-off or closing of the exhaust ports by the piston on the compression stroke. To obtain increased compression and resulting increase of power in the engine the pressure of the scavenging air has 25 been raised, but this involves the use of additional power for driving the pump and still leaves the efficiency of the engine low.

According to this invention, I provide, as 30 close to each cylinder as is practicable, an exhaust controlling valve so actuated as to give full exhaust opening but closing to check or throttle the escaping gases before the closing of the exhaust ports by the piston. Any suitable construction of valve may 35 be employed, but a convenient arrangement comprises a disk valve rotating about a diametrical axis at the same speed as the crank-shaft and adjusted to give the full opening 40 and the required throttling action at the proper points of the piston stroke. Means, such as eccentric or elliptical gearing, may be employed to give the best timing for the free exhaust and throttling operations where 45 constant speed of rotation of the valve is undesirable.

In order that the said invention may be clearly understood and readily carried into effect, I will describe the same more fully 50 with reference to the accompanying drawings, in which:

Figure 1 is an elevation of an engine showing the position of the exhaust controlling valve and a convenient method of driving it.

55 Figs. 2 and 3 illustrate a form of rotating disk valve which may be employed.

Fig. 4 shows a modified form of rotating valve.

Figs. 5 and 6 illustrate a cylindrical type of rotating valve. 60

Fig. 7 shows an ordinary mushroom valve with cam control.

Fig. 8 shows a throttling valve of flap type opening automatically against the pressure of a spring. 65

The illustrations are of a more or less diagrammatic type.

Referring to Fig. 1, the cylinder A of the two-stroke engine is provided with the exhaust ring B to which the exhaust pipe C, 70 forming a valve casing, is fitted and the valve shown in the following figures is placed in the said casing or exhaust pipe. The spindle d of the valve, which is assumed to be of rotating type, is provided with the 75 bevel wheel d' with which engages the bevel wheel e on the shaft E, the other end of which is driven through bevel gearing f from the crank shaft F of the engine. This gearing gives a constant speed rotation to 80 the throttling valve but eccentric or elliptical gearing may be substituted for the simple bevel gearing shown in order to give the best timing for the throttling operation of the valve. 85

Referring to the valve shown in Figs. 2 and 3 the exhaust passage c passing through the valve casing or exhaust pipe C is provided with the rotating disk valve D mounted centrally upon the spindle d, which may 90 be driven as shown in Fig. 1. The disk valve when in the position shown, in which it extends laterally across the passage c, does not quite close the passage and allows the exhaust gases to pass through the narrow 95 annular channel surrounding the disk, this restricted passage giving a pronounced choking action to the gases so that the pressure in the cylinder A at the end of exhaust is substantially above atmospheric pressure. 100 The timing of the valve D is arranged so that the valve approaches the maximum throttling position some time before the engine piston closes the exhaust ports and the throttling takes place during the entry of the 105 scavenging air. The complete closing of the exhaust by the engine piston occurs approximately at the position of maximum throttling by the valve D.

For reversing purposes the gearing driving the valve D need not be altered unless it is desired to develop full power on re-

verse, in which case spiral gearing could be fitted on the shaft E or the valve spindle d to allow of an alteration relatively to the crank shaft of the engine. Thus when the 5 crank shaft is on the dead center with fully open exhaust ports the valve may be advanced to the position indicated by the line α for the forward driving of the engine and the valve may be brought by the spiral gearing to the position γ when the engine is 10 reversed.

A slight modification of the valve is indicated in Fig. 4, the valve D being of the 15 rotating disk type shown in Figs. 2 and 3 but the exhaust pipe or casing C is provided with a small annular bulge c' forming a spherical enlargement which allows maximum 20 throttling of the gases to extend through a period represented by the angle α , as the valve is rotated across the spherical 25 enlargement. By this means the throttling may be rendered more efficient.

In the modification shown in Figs. 5 and 6 the rotating valve D' is of cylindrical form 25 and the exhaust gases pass through the central transverse channel d^2 , the form of the channel being shown in Fig. 5 as contracting toward one end. The part of the valve 30 toward the contracted end of the passage when passing over the opening of the casing will prolong the period of maximum throttling. The exhaust pipe C is formed with a cylindrical portion corresponding to the valve, which however leaves a small annular clearance so that when the valve is not 35 across the passage c the gases can still escape, though at a greatly reduced rate. This valve is rotated as in the case of the disk valve already described.

40 In the modification shown in Fig. 7 an ordinary mushroom valve D² is employed under the control of the cam E, which is so formed as to open the valve D² fully during the earlier stages of the exhaust and to allow 45 it almost to close during the final stages, under the action of the spring e, to provide for the desired throttling effect without actually cutting off the exhaust until the exhaust port is closed by the engine piston.

50 In Fig. 8 an automatic valve D³ is shown consisting of a flap hinged at d^4 and extending across the passage c, the valve being normally held in the position shown in full lines by means of the spring d^3 acting 55 through the arm d^4 on the valve spindle. In the closed position the valve does not completely obstruct the passage c but allows a restricted channel through which the exhaust gases during the final stage of the exhaust 60 are allowed to flow, but during the early stage, when the exhaust pressure is

considerable, the valve D³ is moved back against the force of the spring into a fully open position such as is shown in dotted lines, closing automatically as the pressure 65 of the exhaust gases falls. The throttling action can be adjusted to any required extent by varying the strength of the spring d^3 , so that the valve may be set to give the best throttling effect as found by experiment.

A valve arrangement in accordance with this invention allows of reduction both in quantity and pressure of the scavenging air while providing for sufficient compression 75 and the efficiency of the engine is correspondingly increased by the power saved in the operation of the scavenging pump.

What I claim and desire to secure by Letters Patent of the United States is:— 80

1. In a two-stroke internal combustion engine, a piston, a cylinder provided with an exhaust port controlled by the piston and an exhaust controlling valve adapted to be so actuated as to give full exhaust opening and 85 provided with a small clearance when closed so that on closing before the closing of the exhaust ports by the piston it provides a very restricted channel for the gases which are throttled as they escape just before the 90 closing of the exhaust port by the piston.

2. In a two-stroke internal combustion engine, a piston, a cylinder provided with an exhaust port controlled by the piston, an exhaust channel, and a rotatable exhaust controlling valve in the said channel adapted to open the exhaust channel during the earlier stages of the exhaust but provided with a small clearance when closed so as only partially to close the said channel during the 100 later stages of the exhaust, to throttle the gases before the exhaust is completely cut off by the engine piston.

3. In a two-stroke internal combustion engine, a piston, a cylinder provided with an 105 exhaust port controlled by the piston, an exhaust channel, a rotatable exhaust controlling valve in the said channel having a small clearance when in closed position and means for rotating the said valve so as to 110 close it before the exhaust port is closed by the piston.

4. In a two-stroke internal combustion engine, a piston, a cylinder provided with an exhaust port controlled by the piston, an exhaust channel, a rotatable disk valve in the said channel between which and the valve a restricted passage is left when the valve is transversely across the channel, and means for rotating the said disk valve. 115

JAMES McKECHNIE.
